UNITED STATES PATENT OFFICE

132,622

DESIGN FOR A COMBINED CLOCK AND RADIO DIAL

Thomas C. Johnson, Los Angeles, Calif.

Application August 16, 1941, Serial No. 102,902

Term of patent 3½ years

To all whom it may concern:

Be it known that I, Thomas C. Johnson, a citizen of the United States, and a resident of the city of Los Angeles, in the county of Los Angeles and State of California, have invented a new, original, and ornamental Design for a Combined Clock and Radio Dial, of which the following is a specification, reference being had to the accompanying drawing, forming part thereof.

In the drawing:

Figure 1 is a front elevational view of a combined clock and radio dial showing my new design.

Figure 2 is a side view thereof drawn to a somewhat smaller scale than the disclosure in Fig. 1.

I claim:

The ornamental design for a combined clock and radio dial, substantially as shown.

THOMAS C. JOHNSON.
